READER'S LINE GUIDE

Minnie Woodley, Dallas, Tex.

Application April 7, 1933, Serial No. 664,921

5 Claims. (Cl. 120—33)

This invention relates to line guides or under-alignment especially adapted for stenographic copy work and it has particular reference to such a device particularly useful as an advertising novelty.

The principal object of the invention is to provide a simple, practical line guide of economical construction and possessed of considerable utility not only as a line guide but which likewise may

10 be used as an opener for envelopes, a straight edge and in some cases as a ruler or measuring instrument, which features, although incidental to the prime purpose of the invention, lend materially to its value as an advertising medium.

15 Another object of the invention is to provide a device of the character specified which may be adjusted as to length so as to adapt the same for copy sheets of varying widths and to provide an adjustment easy to make and adding little to the cost of the device.

20 Among the more important objects of the invention is a means by which the line guide is securely held to one or more sheets of copy paper so that it will not easily become displaced thereon, yet allowing for ready movement over the sheet when manipulated by hand. The means by which the line guide is slidably held to the top sheet is arranged to be rotatable and moved out of operative position so that it will not interfere with other uses to which the device may be applied.

25 With the foregoing objects as paramount, the invention has particular reference to its salient features of construction and arrangement of parts which will become manifest as the description proceeds, taken in connection with the accompanying drawing, wherein:—

Figure 1 is a perspective view of a line guide constructed according to the present invention.

30 Figure 2 is a plan view.

Figure 3 is a side elevation.

Figure 4 is a fragmentary view showing the gripping means represented in dotted lines in inoperative position.

Figure 5 is a view on lines 5—5 on Figure 3.

45 Figure 6 shows the invention applied on an ordinary stenographer's note book, and

Figure 7 is a modified form of the construction shown in Figures 1 to 6 inclusive.

50 Continuing with a more detailed description of the drawing, 1 designates a portion of the line guide which may properly be termed a sheath or holder, since this member slidably supports a strip 2 by reason of an upturned edge 3 on the member 1 to frictionally hold the strip 2 in sliding relation to the said member 1. It is true that

when the strip 2 is in extended position as shown in Figure 2, both members 1 and 2 serve as the line guide, it being understood that the upper edge of the device is intended to lie directly beneath each line as the matter is copied, hence the strip 2 and the member 1 is preferably of very thin material although of such rigidity as to maintain proper relation with the sheet of copy material.

As an advertising medium, it is preferred that the device or at least the strip 2 be of light color to distinctly disclose the advertising matter carried thereon and in order that this might be accomplished without detracting from the utility of the device as a line guide, the upper edge *a* of the strip 2 is preferably of a dark color so as to be distinctive with respect to the copy work. The free end of the device, including both the strip 2 and the member 1 is sharpened by cutting obliquely so as to render the same useful as an opener for envelopes and the like. The lower edge of the strip 2 is squared to define a ruler or measuring instrument of any character which may be so designed. This is indicated at *b* in Figure 2.

In order to hold the device for sliding movement on a sheet of copy material, a flexible wire loop 4 is pivotally secured to the sheath or member 1 by means of a brad or rivet 5 of any suitable construction and which loop may be moved to the dotted position shown in Figure 4 so that it will not interfere with any use to which the device may be applied. The loop 4 may be of any suitable shape or design, it being preferred that the sides of the loop extend well beyond the edges of the device itself and bent slightly upward on each side to rise above the common surface of the line guide.

This is borne out in Figure 3 and in order that the desired amount of tension may be had, the loop is shaped with a bend *c* so that at the free intersection of the loop and the sheath, there will be a slight pressure sufficient to bind the sheet of copy paper securely between the loop and the sheath. In fact, the peculiar shape of the loop 4 and its relation to the sheath 1 is such that there will be a slight tension on the copy sheet at all times and the loop will touch the copy sheet throughout. Thus maximum tension is made possible with the least possible weight, yet allowing the device to be moved over the sheet with ease and readiness.

In Figure 7 is shown a modified form of the device just described and is comprised of a single strip of resilient material 6 to which is attached a spring leaf 7 by means of a rivet, brad or the like 8. Increased tension of the leaf 7 in rela-

tion to the strip 6 is obtained by crimping the said leaf 7 at 9 adjacent its point of connection with the strip 6. This crimp 9 serves a function similar to the bends c in the wire loop 4 previously described.

Manifestly, the construction shown is capable of some modification and such modification as is considered within the scope and meaning of the appended claims is also considered within the spirit and intent of the invention.

What is claimed is:

1. A line guide including a tongue portion arranged to lie across a copy sheet and having a resilient wire loop pivoted thereto, whose edges overreach the edges of said tongue portion and arranged to frictionally engage the opposite side of said copy sheet.

2. A reader's line guide including a straight tongue portion arranged to underlie a line on a copy sheet and a wire loop pivoted thereto arranged for frictional contact with the opposite side of said copy sheet.

3. A reader's line guide including a member ar-

ranged to be moved across a sheet of copy material in close relation thereto and a loop member pivoted for rotation on said member and engageable with said copy sheet for sustaining said member in adjusted positions on said copy sheet.

4. A reader's line guide including a member arranged to lie against and be movable over the surface of a sheet of material for underlying the lines on said material and resilient means pivotally connected to said member to lie against and intersect the axis thereof for frictionally interposing said sheet of material to prevent displacement of said member.

5. As a new article of manufacture, a reader's line guide and advertising novelty including a straight edged member arranged to overlie a sheet of copy material and a looped resilient holding means movably secured to said straight edged member and intersecting the axis of the latter opposite its point of securement to frictionally interpose said sheet of material between said member and said resilient means.
